KNOCKING OVER DEVICE FOR FLAT
HOSIERY FRAMESKarl Richard Lieberknecht, Oberlungwitz,
GermanyApplication September 5, 1930, Serial No. 479,911,
and in Germany January 18, 1930

3 Claims. (Cl. 66—109)

This invention relates to a knocking over device for flat hosiery frames, in which the knocking over for loop rows of different length is effected in a simple manner automatically.

5 The essential characteristic feature consists in that between the knocking over comb and the elements actuating the same a yieldable, adjustable connection is inserted, which permits of the comb yielding as soon as a knocking over 10 tension of the loops determined by this connection has been attained.

An embodiment of the invention is illustrated by way of example diagrammatically in side elevation in the only figure of the accompanying 15 drawing.

The knocking over comb 1 is actuated from the shaft 2, which in turn is controlled by cams 3 and roller levers 4. On the shaft 2 several levers 5 are fixed which transmit the rotation 20 of the shaft upon the knocking over comb. According to the invention these levers 5 do not act directly upon the knocking over comb. The levers 5 move independently and their movement 25 is transmitted upon the knocking over comb 1 by an interposed yielding connection, i.e. a pull spring 6 inserted between the elements 1 and 5 and pulling the comb 1 against an abutment 7 on the lower side of the lever 5. The knocking over comb 1 has a lateral arm 9 in 30 which an adjusting screw 8 is screwed, the free end of said screw bearing against the abutment 7. By turning the screw 8 the tension of the spring 6 can be regulated within certain limits.

The cam 3 is of such shape that in long loop 35 rows a just sufficient knocking over tension is obtained. For shorter loop rows the knocking over tension would become too great, when the vertical movement of the needles is the same, as the loops are shorter. When the knocking 40 over tension determined by the tension of the spring 6, has been exceeded, the knocking over comb yields, distending the spring, so that a good knocking over without excessive straining of the loops is obtained.

45 For the pull spring any other suitable spring may be substituted.

For horizontally and vertically movable knocking over it is advisable, to use the spring arrangement for the horizontal movement. In 50 this case the knocking over in vertical direction is adjusted for the short loops and the long loops remain at first loose. Only in the throat, which is commonly used with double movable knocking over, also the row of long loops is 55 sharply knocked over, the spring effect of the

needles in horizontal direction being added to the effect of the spring connection described.

I claim:

1. In a flat hosiery frame according to the cotton system the combination of a knocking over comb, a movable frame carrying said comb, an oscillatable lever adapted to control the movement of said frame, a cam adapted to actuate said lever, and resilient means adapted to allow the yielding of said knocking over comb under strong pressure during the knocking over. 60

2. In a flat hosiery frame according to the cotton system, the combination of a knocking over comb, a slidable frame carrying said comb, an oscillatable lever adapted to control the movement of said frame, a cam adapted to actuate said lever, an adjustable stop on said frame adapted to support said lever, and a spring between said lever and said frame adapted to allow said frame to descend under excessive 75 knocking over pressure to prevent a tearing of the stitches to be knocked over in the case of short sinking of the loops.

3. In a flat hosiery frame according to the cotton system, the combination of a knocking over comb, a frame movable in the direction of its longitudinal axis and carrying said comb, an oscillatable lever adapted to control the movement of said frame, a cam adapted to actuate 80 said lever and resilient means adapted to allow the yielding of said frame and knocking over 85 comb under strong pressure during the knocking over.

KARL RICHARD LIEBERKNECHT.
